Rhosa H. Dunning

UNITED STATES PATENT OFFICE.

RHESA H. DUNNING, OF NORTH SAN JUAN, CALIFORNIA.

IMPROVEMENT IN RIFFLE-BOXES.

Specification forming part of Letters Patent No. 58,079, dated September 18, 1866.

To all whom it may concern:

Be it known that I, RHESA HALL DUNNING, of North San Juan, county of Nevada, State of California, have invented a certain new and useful Riffle-Box for Saving Gold; and I do hereby declare the following description and accompanying drawings are sufficient to enable any person skilled in the art to make and use my said invention without further invention or experiment.

The nature of my invention consists in the employment of a separate box to be placed in a sluice used for hydraulic mining, which receives the gold as it divides the water or falls through the bars of the flume.

Referring to the drawings, Figure 1 represents a section of a flume, sluiceway, and box, taken in line of 5 and 6, as shown in Fig. 4; Fig. 2, also section of flume, box, and sluice, taken in line 3 and 4, Fig. 4; Fig. 3, a section of box, taken in line 3 and 4, Fig. 4; Fig. 4, a top view or plan of box; Fig. 5, cross-section of box.

A, A, &c., represent the flume through which the gravel or dirt and water is admitted over riffle-bars in the usual way, and is placed at right angles with the sluiceway, the tail end extending to within about six inches, more or less, of the outer edge of the sluiceway B, sufficient to allow the gravel to clear itself from the riffle-box C by the force of the water, while the coarser pieces of gold, which have not passed through the riffle-bars, but have been carried to the edge of the tail of the flume, being of a specific gravity nineteen times greater than that of the water, break the current of the water and fall into the box C.

The box C, I construct of wood or other material, so that it will easily slide along the bottom of the sluiceway and not bind at the sides, and place it directly under the tail of the flume at the head of the sluice, reaching to within about six inches, more or less, of the top of the sluiceway.

Across the riffle-box C, I place a dam-wall, D, of plank or other material, near the tail end of the box, leaving a space of about six inches between it and the tail end of the box, and of about one-half the height of the sides and head-board of said box. A very good substitute for this dam-wall may be had by placing a board edgewise across the bottom of the sluice-box; or a bucket or vessel of any kind may be used, in which case the water and débris will be allowed to boil over all around instead of only over one part of the vessel.

It will be found in the operation of my riffle-box that the water, finer gravel, and gold which pass through the riffle-bars of the flume will fall directly into the box, and the force and constant agitation of the water will carry off the débris over the dam-wall D, and out through the tailway of the sluice.

Should the force of the water be so great as to bear over the dam-wall any particles of gold, they being so much heavier than the water and the force exerted by its fall, the gold in passing over the dam-wall will break the current and fall onto the tailway of the riffle-box, where it will remain near the dam-wall, or be found in the riffle below the box in the sluice, and not be carried down to the tail of the sluice and lost, as is often the case where no riffle-box is used.

Having thus described my invention, what I claim, and desire to secure by Letters Patent, is—

The riffle-box C, and dam-wall D, or their equivalents, to be employed for saving gold at any point where there is a divide of water, substantially as described.

In witness whereof I have hereunto set my hand and seal this 16th day of March, A. D. 1866.

RHESA H. DUNNING. [L. S.]
